L. S. GUNDERMAN

MECHANICAL TOY

Filed July 16, 1925

UNITED STATES PATENT OFFICE.

LESTER S. GUNDERMAN, OF PITTSBURGH, PENNSYLVANIA.

MECHANICAL TOY.

Application filed July 16, 1925. Serial No. 43,960.

To all whom it may concern:

Be it known that LESTER S. GUNDERMAN, citizen of the United States, residing at 251 Kennedy Ave., N. S., Pittsburgh, in the county of Allegheny and State of Pennsylvania, has invented certain new and useful Improvements in Mechanical Toys, of which the following is a specification.

This invention is for a mechanical toy of the type in which a miniature vehicle has rapid downwardly travel in a track, power means being provided for raising the vehicle from a lower level to a higher level.

The objects of the present invention are 15 to provide a simple toy which can be cheaply manufactured, the primary object of this invention being to provide means for directing a vehicle down an incline path through a loop to the other end of the track, 20 then by rocking the track the vehicle is raised to a higher level to gravitate back to its initial position.

Referring to the accompanying drawing, Fig. 1 is a top plan view of the toy, with 25 the car removed.

Fig. 2 is a horizontal section on line A—A of Fig. 1 and shows the car in an elevated position.

Fig. 3 is a cross section on line B—B of 30 Fig. 2.

In the drawing the device comprises a base, which is preferably in the form of an inverted shallow tray, upon which is mounted a pair of uprights 7, in the upper end of 35 which is mounted a swinging frame 8, by pivot bearing 9.

In the swinging frame 8 is mounted a loop 10. The pivot bearings 9 being in a line with the center of the loop section 10, at 40 each end of the loop section are removable end sections 11 having a pair of parallel lugs 13 bent downward below the surface of the track, these lugs fit into parallel slots 12 in the loop section in such a manner as 45 to form a substantial detachable joint.

The track is made with these removable sections 11 in order to minimize in space in packing the toy and in shipping. The entire track therefore comprises three sections 10 and 11—11. The outward end of the removable sections 11 have reversely sloping ends 14 and ends 16 forming a stop to prevent a rolling object or vehicle hereafter described from rolling off the 55 track. The sloping ends 14 are for retaining the rolling object from rolling along the

track until it is sufficiently elevated so that it will gain sufficient momentum to gravitate around the loop section 10 of the track.

The rolling object 15 may be of any suitable means, but I prefer to use a wheeled vehicle.

Mounted on the base 6 is a spring motor 17 of any conventional type of clock work mechanism, mounted on the motor shaft is a 60 crank arm 18. This arm is connected to one end of a connecting rod 19 by a pivot pin 20. The opposite end of the connecting rod 19 being connected to the swinging frame 8 by pin bearing 21, in such a manner that the crank 18 of the spring motor rotates, driving the rod 19, the frame 8, and the track section 10 will swing to alternately raise the track sections 11. 70

The operation of the toy may now be described. Assuming that car 15 to be in a position as shown in Fig. 2, the motor rotating, the crank 18 will cause the arm 19 to swing the loop 10 raising one track end 11, the car 15 will descend the incline portion 80 of the track, around the loop section 10 to the opposite end of the track where it is retained until the track is sufficiently elevated for the car to gain momentum enough in its descent to gravitate back to 85 the opposite end of the track and be elevated to its initial position.

I claim as my invention.

1. A mechanical toy comprising a base, a track having reversely incline surfaces, having a loop therein and pivotally supported in the center thereof above the base, car retaining terminals at each end of the track, operating means supported on the base to alternately elevate the ends of the track and 90 a car adapted to roll on the track.

2. A mechanical toy including a base, a loop having a central pivot support above the base, the track at each end of the loop being inclined, means on the base for alternately 100 elevating each end of the track and alternately lowering the opposite end.

3. A mechanical toy having a loop centrally pivoted suspending the track with reversely inclined surfaces, car retaining terminals at each end of the track, operating means on the base to alternately elevate each end of the track and alternately lower the opposite end, and a car adapted to roll on the 105 track.

4. A mechanical toy comprising a base, a track with reversely incline surfaces, a loop

there between pivotally supported above the track, said pivot being substantially the center of the loop, means to alternately elevate and lower the opposite ends of the tracks and a car adapted to roll by gravity on the track.

5. A mechanical toy comprising a base, a track with reversely incline surfaces sloping toward each other, a pivotally suspended loop interposed between the ends of the

track, said point of suspension being substantially in line with the center of the loop, a car retaining portions formed at the ends of the track, and means on the base for rocking the track to elevate an object to 15 gravitate to the opposite end of the track.

In testimony whereof I have affixed my signature.

LESTER S. GUNDERMAN.
